FOUNTAIN PEN

Original Filed March 5, 1925

UNITED STATES PATENT OFFICE.

JOSEPH CHURCHILL ALFORD, OF MABEN, MISSISSIPPI.

FOUNTAIN PEN.

Original application filed March 5, 1925, Serial No. 13,222. Divided and this application filed March 3, 1926. Serial No. 92,017.

This invention relates to fountain pens and is more especially a division of my co-pending application filed March 5, 1925, Serial No. 13,222, patented April 13, 1926, Number 5 1,580,987.

One of the objects of the invention is to provide an improved pump or piston means whereby the pen can be quickly filled, it being possible readily to house the pump portion 10 after the filling operation and without danger of expelling the ink from the pen.

Another object is to provide a structure the pump or piston mechanism of which can be utilized as a convenient means for cleaning the pen.

A still further object is to provide filling mechanism so constructed as to prevent leakage under any conditions.

With the foregoing and other objects in view which will appear as the description proceeds, the invention resides in the combination and arrangement of parts and in the details of construction hereinafter described and claimed, it being understood that changes 20 in the precise embodiment of the invention herein disclosed may be made within the scope of what is claimed without departing from the spirit of the invention.

In the accompanying drawings the preferred form of the invention has been shown.

In said drawings,

Figure 1 is a view in longitudinal section through my improved pen showing the pen projected and in operative position;

Figure 2 is a view partly in elevation and partly in longitudinal section showing the pen withdrawn and covered by its shield;

Figure 3 is a fragmentary view showing the casing and the shield in section and the 40 other parts in elevation;

Figure 4 is a fragmentary view showing the casing, barrel and shield in section and the pen holder in elevation;

Figure 5 is a fragmentary view in longitudinal section showing the manner of bringing the piston elements into proper assemblage;

Figure 6 is a perspective view of the piston elements when assembled;

Figure 7 is a perspective view of the nib shield;

Figure 8 is a view in transverse section on the line 8—8 of Figure 2;

Figures 9 and 10 are views in section on the lines 9—9 and 10—10, respectively, of 55 Figure 1;

Figure 11 is a view in section through the piston ring.

1 represents the casing of my improved fountain pen. This casing 1 is cylindrical 60 throughout the greater portion of its length but at its forward end is tapered as shown at 2. The casing 1 encloses an ink barrel 3 which is of general cylindrical form and which has an annular flange 4 adjacent its 65 rear end. An externally threaded sleeve 5 fits the outer end of the barrel and is screwed into the casing, as indicated at 6, and against the flange 4 so as to hold the barrel against longitudinal movement but permit it rotary 70 movement.

A stuffing box 7 constituting a threaded plug, is screwed into the end of the barrel 3, as shown at 8, and a milled collar 9 is screwed onto the end of the barrel 3, abuts against 75 the casing 1 and is fixedly secured by a jam screw 10 projected through the collar and against the barrel. The collar 9 has an internally threaded portion 11 to receive an externally threaded plug 12, the latter being 80 also milled or roughened to facilitate its turning. This plug 12 is fixedly secured to a piston rod 13 which projects through the stuffing box 7 into the ink barrel, as shown.

The forward end of the ink barrel has a 85 restricted ink passage 14 into which the reduced end 15 of a longitudinally grooved feed bar 16 is guided. The barrel 3 has at its forward end a cylindrical extension 17 enclosing the inner portion of the feed bar and 90 also receiving a sleeve 18 around the feed bar. The pen 19 is securely held against the feed bar when projected between the same and the sleeve 18, as clearly shown.

On the extreme inner end of the rod 13 an 95 enlargement 20, constituting a valve, is provided and is adapted when the plug 12 is screwed all the way in to close against a seat 21 and prevent the passage of the ink through the restricted portion 14.

The end of the rod 13 adjacent the valve 20 is screw-threaded as shown at 22, and on this

threaded portion 22 a spider 23 has screw-threaded engagement, and between the spider 23 and the valve 20 a piston ring 24 is mounted which fits the barrel 3 but has a central opening necessarily larger than the rod 13.

On the inner end of the stuffing box 7 I provide lugs 25 between which projections 26 on the spider 23 are adapted to be positioned to hold the spider against turning movement when drawn to the position shown in Figure 5.

The casing 1 has longitudinal grooves 27 which receive laterally projecting keys 28 on a ring 29 which constitutes a portion of my improved shield A. The position of these keys 28 and the grooves 27 prevent turning movement of the shield, but said ring is also formed with inwardly projecting keys 30 which engage in spiral grooves 31 in the cylindrical barrel extension 17 so that when the barrel is turned a longitudinal movement is imparted to the ring 29. This ring 29 has a pair of forwardly projecting spring arms 32 carrying semi-conical plates 33 at their forward ends, which when projected forwardly engage the tapering forward end of the casing 1 and move toward each other to enclose the pen, as shown in Figure 2.

The sleeve 18 around the pen and pen holder is formed with a key or keys 34 to move in spiral grooves 35 in the cylindrical barrel extension 17 so that when the barrel is revolved the pen holder and the nib are projected or withdrawn as the case may be.

The grooves 31 are oppositely coiled so that when the pen is projected, the shield A is withdrawn and when the pen is withdrawn, the shield A is projected. Hence, when the pen is in its outward position, the shield is in the casing, and when the pen is moved inwardly the shield functions to cover the pen and the forward end of the nib holder.

Turning movement is imparted to the barrel by manual manipulation of the collar 9. When the pen is not desired for use the valve 20 can be moved against its seat 21 to prevent the possibility of leakage.

To fill the pen the operation is as follows:

The rod 13 is drawn outwardly which will cause the enlargement 20 to engage the ring 24 and move it with the spider 23, forming a suction plunger which will suck the ink into the barrel. When it is desired to clean out the barrel and impart a reciprocating movement to the plunger, the operation will be as follows: The plug 12 is unscrewed to release it from the cap 9, and the rod 13 is drawn outwardly until the spider 23 is against the inner end of the stuffing box 7 when the lugs 26 will engage the lugs 25 and the spider will be held against turning movement. When the rod 13 is drawn outwardly as explained, the threaded portion 22 will slide into the bore in the stuffing box which is not screw-threaded. While in this position the rod 13 is turned so as to screw the rod through the spider and draw

the enlargement 20 against the ring 24 and compress the ring between the enlargements and the spider, thus forming a complete piston or plunger. The rod is then moved inwardly so as to move the piston in a direction to expel the air, which is a movement toward the nib end of the pen.

In filling, the pen is inserted in the ink and the piston is drawn rearwardly, sucking the ink into the barrel and again bringing the piston assemblage to the position shown in Figure 5. The pen is projected or withdrawn by turning the cap or collar 9, and, as above explained, when the pen and pen holder are withdrawn the shield moves so as to enclose the pen, and when the pen is projected the shield is withdrawn through the medium of the keys and grooves such as above explained.

The sleeve 18 has laterally projecting pins 40 which move in longitudinal grooves 41 in the casing 1 to prevent turning of the sleeve.

What is claimed is:

1. A fountain pen, including a casing, an ink barrel in the casing, a fixed member closing the end of the ink barrel, a rod projecting through said fixed member and having a screw-threaded inner end, an enlargement on said screw-threaded inner end, a spider secured on said threaded inner end, a piston ring loose on the threaded end between the spider and the enlargement, and lugs on the fixed closure of the barrel and on the spider adapted to hold the spider against turning movement when the rod is withdrawn so as to allow the rod to be turned and move the enlargement toward the spider to clamp the ring and form a piston assemblage.

2. A fountain pen including a casing having an ink barrel, there being an ink outlet at one end of the barrel, a rod slidably and rotatably mounted in the other end of the barrel, an enlargement at one end of the rod constituting a valve for closing the outlet, said rod having a screw threaded portion adjacent the enlargement, a member constantly engaged by the screw threaded portion and movable with the rod, cooperating means upon said member and the closed end of the barrel for holding said member against rotation while in contact with the end of the barrel, said rod constituting means for moving the member into and out of engagement with said end of the barrel, a ring loosely mounted on the threaded portion of the rod between said member and the enlargement, said threaded portion, when rotated with the rod, constituting means for clamping the ring between the enlargement and the member while said member is held against rotation.

3. A fountain pen including a casing, an ink barrel in the casing having an ink outlet passage surrounded by a valve seat, a closure for one end of the barrel, a rod mounted to slide and rotate within the closure, there being an enlarged screw threaded portion on the

rod adjacent the valve, a piston ring loosely mounted on said threaded portion, a spider engaging the threaded portion of the rod, said spider and valve constituting means for limiting the movement of the piston ring longitudinally of the rod, lugs upon the spider, and lugs upon the closure of the barrel, said rod being shiftable longitudinally to bring the lugs of the spider into engagement with the lugs on the closure and being rotatable while

said lugs are in engagement, to shift the spider along the threaded portion of the rod, thereby to clamp the piston ring against or release it from the valve, said valve, piston ring and spider, when clamped together, co- 15 operating to form a tight piston assemblage.

In testimony that I claim the foregoing as my own, I have hereto affixed my signature.

JOSEPH CHURCHILL ALFORD.
